UNITED STATES PATENT OFFICE.

OMER VAN COLE, OF MONTE VISTA, COLORADO.

TERRET-RING.

SPECIFICATION forming part of Letters Patent No. 509,004, dated November 21, 1893.

Application filed May 11, 1893. Serial No. 473,771. (No model.)

To all whom it may concern:

Be it known that I, OMER VAN COLE, a citizen of the United States, residing at Monte Vista, in the county of Rio Grande and State 5 of Colorado, have invented a new and useful Terret-Ring, of which the following is a specification.

My invention relates to improvements in terret-rings; and has for its object the provision of an attachment or formation of a terret or other ring, as for instance the ring of a hitching-post, whereby the same is adapted to secure in a convenient manner the loose or free end of a hitching strap so that the same 15 may be readily applied and removed without the necessity of knotting.

With these and other objects in view the invention consists in certain features of construction hereinafter specified and particularly pointed out in the claim.

Referring to the drawings:—Figure 1 is a perspective view of a terret-ring constructed in accordance with my invention, said ring being of the usual formation and having applied thereto an attachment whereby the objects of the invention may be accomplished. Fig. 2 is a similar view, the attachment being formed in conjunction with the ring. Fig. 3 is a perspective view of the upper end of a 25 hitching post provided with a ring embodying the invention. Fig. 4 is a detail in perspective of the attachment illustrated in Fig. 1.

Like numerals of reference indicate like parts in all the figures of the drawings.

Referring more particularly to Fig. 1, 1 designates an ordinary terret-ring having formed upon its under side the neck 2, and below the same the reduced and threaded shank 3. From one side of the neck 2 in line 35 with the ring 1 there extends outwardly an arm 4, the same being somewhat of L-shape in that it consists of a lower substantially horizontal branch, and an upwardly disposed and slightly inclined branch or portion, the same finally terminating in a rearwardly disposed portion 5. The inner end of the arm 4 is enlarged to form a head 6 and is provided with a perforation 7 adapted to fit the stud 3, said stud passing therethrough and into 40 the saddle of the harness, not shown. It will be seen that the neck 2 rests upon the head

6 and clamps the same securely upon the saddle. The arm is preferably formed of sheet metal when employed as an attachment to those terret-rings now in use and where it is 55 undesirable to exchange the same for the improved terret-ring. It will be seen, however, that the arm may be otherwise formed than of sheet metal and I do not limit the invention to such.

In Fig. 2, 8 designates the ring, 9 the neck, and 10 the stud. Formed integral with the neck 9 is the L-shaped arm 11 consisting of a horizontal lower portion, an outer upwardly inclined portion, and a laterally disposed terminal 12. This form of ring is designed to be substituted for that now in use and illustrates the manner in which the invention may be employed in connection with the manufacture of the ring.

In Fig. 3, 18 designates an ordinary hitching post, into the upper end of which is let a ring 19 similar to that shown in Figs. 1 or 2, the same having extending from one side, as shown in Fig. 2, a rigid, integrally formed L-shaped arm 20, having its upper inclined outer portion bent as at 21. It will thus be seen that the arm may be applied to rings already in use; may be manufactured upon the same; and applied to hitching-posts, and in 65 fact, I would here state that it may be used in connection with any ring to which it is desired to connect a strap or rope. In the present instance, however, it is particularly intended for connecting the loose or free end 80 of a hitching strap, which strap I have designated by the numeral 22.

The operation of attaching the hitching-strap to the arm, and as best illustrated in Fig. 2, is as follows: A convenient distance 90 from the bit, at which point the front end of the strap is attached by means of the usual snap-hook or buckle, the said strap is doubled upon itself, is passed rearward along the outside of the arm, and forwardly through the 95 ring. It is then carried laterally to one side toward the arm and engaged over the same, the bent end of the arm preventing any disengagement. The short terminal of the strap is under the long terminal, and dangles 100 loosely below the point or points where the long terminal overlies and clamps it. The

abrupt bends given the strap serve to maintain it in position and prevent it from coming loose by any jolting or subsequent shaking it may receive. To disengage the strap it is simply necessary to raise the loop from over the L-shaped arm and draw it rearward through the ring. It will be seen that the connection of the strap with the ring does not in any way interfere with the free movement of the lines or reins through the ring, in that the hitching strap is snugly pressed against one side of the ring.

It will be understood that in practice where the ring is applied to single harness it is located upon the left side of the saddle and the arm extends outward. When applied to double harness, one ring should be placed on left side of saddle and the other on the right side of saddle, so that the rings should be made rights and lefts.

In unhitching, the device will afford a convenient means for securing the reins in a supported position.

Having described my invention, what I claim is—

The herein-described device for holding hitch-straps, comprising a horizontal arm projected from one side of the base of a line-ring and having an outer upwardly disposed portion terminating substantially opposite the center of the ring, and provided at said point with a laterally disposed extension, substantially as specified.

In testimony that I claim the foregoing as my own I have hereto affixed my signature in the presence of two witnesses.

OMER VAN COLE.
